UNITED STATES PATENT OFFICE.

MIKE J. DONAHOE, JR., OF SEDALIA, MISSOURI.

ALL-METAL FENCEPOST.

Application filed December 19, 1923. Serial No. 681,533.

To all whom it may concern:

Be it known that I, MIKE J. DONAHOE, Jr., a citizen of the United States, residing at Sedalia, in the county of Pettis and State 5 of Missouri, have invented certain new and useful Improvements in All-Metal Fenceposts, of which the following is a specification.

My invention relates to an all metal fence 10 post.

One object of this invention is to provide a fence post of this class having means for stretching the wire or the netting not only when the fence is being erected but at any 15 other time if the wire or netting becomes slack.

Another object of the invention is to so construct the fence post that it will not be lifted out of the ground by frost as is commonly the case with fence posts of ordinary 20 design. The post is further provided with means for preventing it from being turned or twisted out of its erected position in the ground.

25 The post is, moreover, reinforced in the part where it experiences the greatest bending strain, that is to say, immediately above and below the ground.

In the accompanying drawing, the fence 30 post, forming the subject matter of the present invention, is illustrated, and—

Figure 1 is a side elevation of the fence post;

Figure 2 is a front elevation thereof;

35 Figure 3 is a transverse section on an enlarged scale along line 3—3 of Figure 2;

Figure 4 is another transverse section along line 4—4 of Figure 2, and

40 Figure 5 is a side elevation of a slightly modified form of the post.

The fence post consists mainly of a steel or angle iron having two flanges 10 forming substantially a right angle to each other as seen in Figures 3 and 4. The post is of 45 sufficient length to hold it firmly in the ground and is preferably provided with a rearwardly extending wing 11 firmly united with the angle iron along its apex on the part intended to be embedded in the ground.

50 As best seen in Figure 4 the vertical plane in which this wing is situated bisects the angle formed at the apex of the two flanges 10 of the post. This wing is preferably beveled, as at 12, on its upper side and is 55 not visible above ground when the post has been erected.

Along the forward edges of the flanges 10 are preferably provided downwardly directed notches 13 adapted to temporarily receive the barbed wires 23 while the fence 60 is being erected but they are not absolutely necessary as when the wires have been permanently secured they cannot shift up and down on the post.

In the angle formed between the flanges 65 and reaching a short distance up and down on the post from the ground line is provided a reinforcement 14. This is for the purpose of preventing the bending of the post at the ground line where such bending generally 70 takes place on account of the great strain at this point.

In the vertical central plane of the fence 75 post is provided a number of apertures 15, three of which are shown in the drawing and adapted to engage the shanks of clamping eye bolts 16 which are threaded at their ends to engage with clamping nuts 17.

Reference numeral 18 represents a shoe 80 which embraces the fence post and is adapted to slide up and down thereon. This shoe may be secured in any suitable position by means of a set screw 19 drawn up to contact with one of the flanges 10 of the fence post. This shoe has a centrally situated inwardly 85 directed hook or eye 20 which is adapted to engage the lower end of a securing rod 21 which also engages in the loops 22 of the clamping bolts 16.

In order to build a fence the posts are set 90 up as indicated in Figures 1 and 2. That is to say, if the ground is not too hard a hole is dug for the post which is then placed therein in upright position so that the wing 11 is entirely below the ground line and the soil 95 is thereupon packed in the usual manner tightly around the post. The shoe 18 is slipped over the post from the upper end thereof and placed near or on the ground as seen in said figures. The shoe is thereupon secured by the set screw 19.

The wires 23 are then placed temporarily 100 in the notches provided along the edges of the flanges and stretched in the usual manner between the ends of the fence. The rod 21 is then inserted in the hook 20 leaning forwardly as indicated in dotted lines in Figure 1 with its handle end 24 some distance away from the top end of the fence post 105 while previously the clamping bolts 16 have been slipped loosely on the rod 21. The rod 110 is now swung toward the post, the hook 20

acting as the fulcrum and the lowermost of the clamping bolts 16 entered in a corresponding aperture 15 in the fence post and the bolt drawn up by means of the clamping 5 nut 17 toward the apex of the fence post. The other clamping bolts 16 are then entered in the same manner and drawn up by the respective nuts 17 in the fence post. As these bolts are tightened the slack in the wires is 10 entirely taken up as the securing rod 21 contacts with all of the wires in the fence. It is evident that if the wires should become slack subsequently to the erection of the fence, a further tightening is easily accomplished by 15 drawing up the nuts more firmly on the clamping bolts 16 and the wires will be drawn inwardly in the fence post as best indicated in Figure 3.

When the posts are intended for very hard 20 ground in which freezing would have no effect on them, they may be pointed at their lower ends, as indicated at 24 in Figure 5 of the drawing.

After the wires have been secured by the 25 clamping bolts 16 and the securing rod 21 as already described, they cannot shift up and down on the post even if no notches are pro-

vided in the edges thereof. This is particularly the case when wire netting is used for the fence and the notches may then be left 30 out entirely. The notches have been left out in the post shown in Figure 5 which is otherwise identical with the post shown in the other figures.

Having thus described the invention, what 35 is claimed as new is:

An all metal fence post comprising an angle bar having diverging flanges extending the full height of the bar and both adapted to engage and support fence wires, eye bolts 40 engaged through the apex of the angle bar with their eyes between the flanges thereof, nuts mounted on the ends of said bolts to be turned home against the bar, a securing rod engaged through the eyes of said bolts in 45 front of and in contact with the fence wires, a shoe encircling and adjustably secured upon the angle bar at the lower portion thereof, and a hook carried by the shoe and extending inwardly between the flanges of 50 the bar and gripping the lower end of the securing rod.

In testimony whereof I affix my signature.

MIKE J. DONAHOE, Jr. [L.S.]
